UNITED STATES PATENT OFFICE.

HARPER F. SMITH, OF PHILADELPHIA, PENNSYLVANIA.

VAPOR-BURNER.

SPECIFICATION forming part of Letters Patent No. 634,705, dated October 10, 1899.

Application filed June 28, 1897. Serial No. 642,582. (No model.)

To all whom it may concern:

Be it known that I, HARPER F. SMITH, a citizen of the United States, residing in the city and county of Philadelphia, State of Pennsylvania, have invented a new and useful Improvement in Vapor-Burners, which improvement is fully set forth in the following specification and accompanying drawings.

My invention consists of improvements in vapor-burners embodying a burner or tip of novel construction and means for intensifying the heat of said burner for causing effective vaporization.

It also consists of novel means for directing vapor or gas upon the supply-tube for primarily heating the hydrocarbon or other fluid employed.

It also consists of a distributor within the burner or tip for deflecting the burning vapor upon the main portion of the body of the device, so as to highly heat the same for perfecting the vaporization.

It also consists in providing the burner with flanges at the sides thereof for holding the flame within the burner.

Figure 1 represents a side elevation of a vapor-burner embodying my invention, one of the deflector-plates thereof having been removed. Fig. 2 represents a vertical section thereof. Figs. 3, 5, 7, 8, 9, and 10 represent side elevations of other forms thereof. Fig. 4 represents a vertical section of Fig. 3. Fig. 6 represents a vertical section of Fig. 5. Fig. 11 represents a vertical section of Fig. 10.

Similar letters of reference indicate corresponding parts in the figures.

Referring to the drawings, A designates the supply-pipe of a vapor-burner, and B designates the valve thereof, the latter being generally known as a "needle-valve."

C designates a chamber for mixing air with the vapor, the same being in communication with the pipe A, the valve B being intermediate of said pipe and chamber.

D designates an expansion-chamber, which is above the chamber C and communicates therewith.

F designates an air-inlet, which in the several figures opens into the mixing-chamber C and is of the form of a tube or nozzle or simply an opening in said chamber.

Above the expansion-chamber D is the

burner proper, G, which consists of the oblique plates H and J, which rise from the walls of said expansion-chamber, the plate H being formed with the respective wall, while the plate J is secured, as at J', to the opposite wall by the screw or screws K or other suitable means, it being evident that the vapor burns in the expansion-chamber and burner proper to the tip thereof and is also injected against said plates, thus highly heating the expansion-chamber and the burner proper, whereby the vaporization is effectively accomplished throughout the entire device.

In order to heat the supply-pipe A, whereby the inflowing hydrocarbon or other fluid is primarily heated and partially vaporized, there is connected with the side of the chamber C or expansion-chamber D a deflector L, which consists of an inclined plate located over said pipe A, forming a chamber M, which is in communication with the chamber C by means of the duct N, the latter serving to direct some of the vapor into said chamber M, which when ignited is deflected or impinged against the chamber M, thus highly heating the same. Within the space between the said plates H and J of the deflector or tip is a distributor P, which serves to direct or throw the burning vapor upon the plate H for increasing the intensity of the heat of the latter, and the sides of said plate have flanges Q thereon for holding the flame within the burner.

In Figs. 3 and 4 I show the plate J as partially convex or swelled, as J², thus producing an enlarged chamber within the plates H and J, causing additional heat to be held and more or less air to be directed to the heat and flame by either partially or wholly deflecting the upper plate to or below the flanges on the side of the lower plate, the volume of the air and heat being regulated by the degree of the convexity or swell of said plate.

Having thus described my invention, what I claim as new, and desire to secure by Letters Patent, is—

1. A vapor-burner having a supply-pipe with a controlling-valve, an air-mixing chamber in communication with said supply-pipe and provided with an air-inlet, an expansion-chamber above said mixing-chamber, and oblique plates inclining in the same direction

and rising from the walls of said expansion-chamber and having their upper ends forming the burner-tip, the latter being located out of alinement with said expansion-chamber.

5. 2. A vapor-burner having a fluid-supply pipe with a controlling-valve, an air-mixing chamber in communication with said fluid-supply pipe and provided with an air-inlet, an expansion-chamber above said mixing-chamber, the oblique plates H and J inclining in the same direction from the walls of said expansion-chamber and having their upper ends forming a burner-tip at one side of said expansion-chamber, said plate J having a convex portion.

3. A vapor-burner having a fluid-supply pipe, a controlling-valve, an air-mixing chamber in communication with said fluid-supply pipe and provided with an air-inlet, an expansion-chamber in communication with said air-mixing chamber, the oblique plates H and J inclining in the same direction from the walls of said expansion-chamber, their upper ends forming a burner-tip located at one side 25 of said expansion-chamber and the distributor P between said plates, said plate J and distributor P being detachable from said burner.

4. A vapor-burner having a fluid-supply pipe, a controlling-valve, an air-mixing chamber in communication with said fluid-supply pipe, and provided with an air-inlet, an expansion-chamber in communication with said

air-mixing chamber, the oblique plates H and J inclining in the same direction from the walls of said expansion-chamber, their upper 35 ends being juxtaposed out of alinement with said expansion-chamber and forming a burner, and a distributor located between said plates.

5. In a burner, a supply-pipe, a valved passage leading therefrom to an expansion-chamber, a deflector extending from the burner toward said supply-pipe, thereby forming a chamber, the latter being in communication with said passage, oblique plates inclining 40 in the same direction from the walls of said expansion-chamber, and a distributor between said plates, said distributor terminating in proximity to said expansion-chamber.

6. A vapor-burner, having a supply-pipe 50 with a controlling-valve, an air-mixing chamber in communication with said supply-pipe and provided with an air-inlet, an expansion-chamber above said mixing-chamber, and oblique plates inclining in the same direction from the walls of said expansion-chamber and having their upper ends forming the burner-tip, the latter being out of alinement with said expansion-chamber, and one of said plates being detachable.
